UNITED STATES PATENT OFFICE

ULYSSES G. SKELLY, OF LOS ANGELES, CALIFORNIA

OIL CASING PLUG

Application filed June 25, 1930. Serial No. 463,689.

The invention forming the subject matter of this application is a fire extinguisher for oil well casings, and has for its object to provide a very simple and highly efficient instrument for this purpose, and one which can be very readily operated.

The invention includes mechanism for positioning the extinguisher vertically over the oil casing and for releasing the extinguisher to allow it to fall by gravity when the axis of the extinguisher—in the form of a tapered plug—is in alignment with the axis of the casing.

Another object of the invention is to provide the extinguisher plug with means which not only locks the plug in its fire extinguishing position in the end of the casing, but also embraces this end to prevent bursting thereof by the impact of the tapered end or part of the extinguisher plug.

Other objects of the invention will become apparent as the detailed description thereof proceeds.

In the drawings:

Figure 1 is a side elevation of the extinguisher-plug supported coaxially with and vertically over an oil well casing; and

Figure 2 is a side elevation of the plug itself in position in the end of the casing, which is shown in this figure and in Figure 1 in vertical section.

In Figure 1 of the drawings, the extinguisher-plug is shown as a heavy spherical mass suspended vertically over the oil casing 1, and includes the spherical part 2 having a cylindrical extension 3 depending therefrom and terminating in a conical member 4, the extension 3 and member 4 having a common axis passing through the center of the part 2. A clamping annulus 5 fits frictionally over the cylindrical extension 3, and shaped to form a downward extension 6 which is bent inwardly and upwardly to form an annular flange 7 adapted

to engage the top 8 of the casing 1 when the extinguisher plug is in operative position on the said casing. The operative position of the extinguisher-plug is shown in Fig. 2 of the drawings. Particular attention is directed to the fact that, in this last

named position, the bulged inner part 9 of the clamping annulus is in clamping contact with the outer wall of the casing 1. This clamping annulus, however, is formed originally so that the annular part 9 thereof will just clear the outer cylindrical surface of the casing 1 and offer no resistance to the proper seating of the extinguisher-plug in the open end of said casing.

The spherical part 2 of the extinguisher-plug is provided with a yoke 10 adapted to receive the jaws 11 and 12 of a pair of tongs mounted to swing freely about a pivot 13 and having a pair of arms 14 and 15 disposed on opposite sides of the said pivot, the said pivot 13 being suitably supported by a member 16 from the hook 17 of a derrick used to locate the extinguisher-plug vertically over the casing 1. The hook 17 is supported by any suitable means, such as the cable 18 which forms part of the derrick equipment, not otherwise shown herein.

The upper part of the arm 15 is provided with a pivot 20 about which is swung the clevis 21, having a cable 22 attached to its free end to swing it from the operative position, shown in full lines in Fig. 1, to the dotted line position shown in the same figure. The clevis is formed with a slot 23 having a curved outer end wall 24 adapted to slide freely over the curved end 25 of the arm 14 whenever the cable 22 is pulled upwardly.

It will be noted that the lower inner edges of the jaws 11 and 12 are shaped so that the weight of the extinguisher-plug will cause the jaws to spring apart whenever the clevis 21 is moved from its operative to its inoperative position. It will also be noted that this clevis when raised to its inoperative position, clears the upper end of the arm 14 and permits the arms and jaws of the weight supporting tongs to swing apart and allow the extinguisher-plug to drop.

It is immaterial what mechanism is used to carry the extinguisher-plug to the casing and locate it properly over the casing so that, when released, the plug will fall by gravity into the open end of the casing and smother any fire which may be raging there-

in. It is also immaterial whether the plug be spherical or cylindrical in its outer end part. It is essential that the plug be heavy enough to overcome the upward pressure of the gases emerging from the casing, that its lower end be tapered so as to offer the minimum of resistance to the emerging gases, and that its intermediate part be cylindrical and of slightly greater diameter than the internal diameter of the casing.

10 It is preferable to make the several parts of the extinguisher-plug separable from each other, so that they can be readily assembled and disassembled. Accordingly, the spherical part 2 is diametrically bored to receive the shank 26 extending from the yoke 10 and screwthreaded at its free end to be screwed into a corresponding screwthreaded bore 27 formed axially in the cylindrical extension 3 of the plug.

15 The upper end of the extension 3 is slightly reduced to form a shoulder 28 which serves as a means for detachably clamping the annulus or sleeve 5 in proper position 25 against the spherical part 2, when the parts thereof are assembled as shown in the drawings. Preferably, too, the rough tool marks of the lathe are allowed to remain on the extension 3 in order to increase the frictional grip between the plug and the casing 30 when the plug is positioned thereon.

20 In the operation of the invention, the plug is positioned vertically over the open end of the casing, with the axes of the plug and casing as nearly as possible coincident. The clevis 21 is then pulled up to inoperative-dotted line-position, and the weight of the plug causes it to fall into the open end of the casing to close said end and smother the fire in the casing. In the closing position, the sleeve 5 embraces the end of the casing and prevents the splitting thereof, and also serves as an additional means for holding the plug in its fire-extinguishing position. 45 When the fire is extinguished, the plug may be removed very readily by unscrewing the bolt 26 and removing the spherical part 2 and the sleeve 5 and then screwing the bolt again into the extension 3 to effect removal thereof by connecting the yoke 10 to the hook 17 of the derrick.

50 It is immaterial just what particular type of derrick is used to position the extinguisher-plug over the open end of the well casing 1. It will be obvious that any kind of a truck, either on a track or on wheels independent of a track, may have its front end provided with some kind of a positioning notch adapted to engage the side of the casing 1, and may have the derrick mechanism located relative to this positioning notch so that when the notch engages the casing, the tong mechanism shown in Fig. 60 1 will be properly located to drop the extinguisher plug into the open end of the

casing. The tongs mechanism forms an essential part of my invention; but the derrick and truck mechanism may be supplied very readily by any person skilled in this art.

70 While I have shown and described a specific form of extinguisher-plug and operating mechanism therefor, it must be understood that my invention is not to be considered as limited to the form shown, nor 75 in any other manner, except as expressly limited by the scope of the claims appended thereto.

What I claim is:—

1. A fire extinguisher-plug for gas and oil 80 well casings comprising: a cylindrical body adapted to fit tightly the inner periphery of the casing to which it is intended to be applied, a tapered extension on one end of said body, and a sleeve secured to the other end 85 of said body and adapted to fit the outer periphery of said casing when the body is seated therein.

2. A fire extinguisher-plug for gas and oil 90 well casings comprising: a cylindrical body adapted to fit tightly the inner periphery of the casing to which it is intended to be applied, and a sleeve detachably secured to said body and adapted to fit tightly around the outer periphery of said casing when the said 95 body is seated therein.

3. A fire extinguisher-plug for gas and oil 100 well casings comprising: a cylindrical body adapted to fit tightly within the inner periphery of the casing to which it is intended 100 to be applied, a conical extension on one end of said body, a weight of larger diameter than that of said body, a sleeve adapted to fit tightly around the outer periphery of said casing, and means for detachably securing said weight and sleeve to said body. 105

4. A fire extinguisher-plug for gas and oil 110 well casings comprising: a cylindrical body, adapted to fit tightly within the inner periphery of the casing to which it is intended 110 to be applied, a conical extension on one end of said body, a weight, a sleeve adapted to fit tightly around the outer periphery of said casing, and means extending through said weight and sleeve to secure said weight 115 and sleeve detachably to said body.

5. A fire extinguisher-plug for gas and oil 120 well casings comprising: a cylindrical body adapted to fit tightly within the inner periphery of the casing to which it is intended 120 to be applied, a tapered extension on one end of said body, a spherical weight having a diametral bore therethrough, a sleeve adapted to fit tightly around the outer periphery of the said casing, and a yoke member having a shank extending through said weight and sleeve and screwthreaded into said body to secure said weight and sleeve detachably to said body. 125

6. A fire extinguisher-plug for gas and oil 130

well casings comprising: a cylindrical body adapted to fit tightly within the inner periphery of the casing to which it is designed to be applied, a conical extension on one end of said body, a sleeve on the other end of said body and adapted to fit tightly around the outer periphery of said casing, and means for detachably connecting said sleeve to said body, said extension sleeve and body having a common axis.

10 7. The combination with the cylindrical casing of an oil or gas well of an extinguisher-plug having a cylindrical body adapted to fit tightly within the inner periphery of said casing, and a sleeve detachably connected to said body and adapted to fit tightly around the outer periphery of said casing, means for positioning said body and sleeve vertically above the open end of said casing, and means for releasing said positioning means to cause the plug to fall into and seal the open end of said casing with the said sleeve embracing the outer periphery of said open end.

15 20 25 In testimony whereof, I have signed my name to this specification.
